VARIEGATED SURFACE AND DISPLAY
MATERIAL AND DEVICEAubrey Evelyn Taylor, Malvern, Melbourne,
AustraliaApplication March 31, 1934, Serial No. 718,483
In Australia July 23, 1932

11 Claims. (Cl. 41—24)

This invention relates principally to variegated surfaces, particularly when produced as printed artistic matter, in imitation of textiles, knitted goods and the like, for use in advertising, on street hoardings in conjunction with known display devices, signs and apparatus, or as original signs, and generally for ornamental and display purposes.

The invention may be applied to many purposes as, for example, to simple or complex illustrations printed on paper or the like when innumerable variations, patterns or designs, colour effects, contrasts and shot-like effects may be readily obtained. Paper printed in accordance with the invention is particularly useful in the manufacture of cartons and packages for goods. The invention, however, may also be employed with advantage in preparing street advertising hoardings and painted signs when different colour effects may easily be produced, dependent upon the direction of approach and/or the station point of the observer. In this connection the invention provides a distinct advantage in that in its ordinary application it provides a sign or illustration which will more frequently be required, that is a sign which varies in colour when viewed from different angles but appears multi-coloured when viewed frontally and which always maintains its outline and is clearly readable as and 30 remains the same sign, or matter, regardless of the observer's position. The invention possesses the advantage that it obtains these effects and advantages on one surface and/or on one element when so desired and under suitable or appropriate conditions of usage.

More specifically one of the principal objects of the invention is to provide methods of embossing printed matter to cause patterns to appear after printing and also colour changes in the patterns when the material is viewed from different stand points, and this object may be achieved by colour printing by several successive impressions or by multi-colour printing by one impression and then in either instance imparting a different pattern or design and/or colour effects to the printed matter by embossing it in accordance with the invention. In some instances, however, embossing in accordance with the invention may be undesirable, for example, in some cases of printing in accordance with the invention to imitate textiles, knitted goods, hosiery and the like when suitable graining or a paper of roughened surface may be used to enhance the printed effect if necessary.

55 Referring to the drawing:

Figure 1 is a view showing parallel lines crossed at right angles intended to be printed in a plurality of different bands of colour A, B, C, by one impression of the printer's block.

Figure 2 is a view showing parallel lines crossed at right angles intended to be printed first in a plurality of different bands of colour A, B, C, by one impression of the printer's block and then to be printed with a plurality of different bands of colour D, E, F, at right angles to the bands A, B, C, by another impression of the printer's block.

Figure 3 is a view showing parallel lines of different conformation or contour which when overprinted in suitable different colours cause a third unprinted colour to apparently appear in the interstices between the overprinted lines.

Figure 4 is a view showing parallel crinkly or wavy lines which when associated or over-printed by straight, sinuous, or other lines of appropriate pitch or conformation and distance apart form patterns or designs resembling knitted goods or textiles and the like.

Figure 5 is a view of a surface printed with parallel sinuous lines crossed at right angles.

The invention is directed to the production of variegated surfaces through the provision of printing a sheet with an arrangement of substantially parallel lines of any desired characteristics and over-printing the initial lines with other lines of desired characteristics in contour, colour, spacing and the like to provide a patterned surface, together with an embossing of the patterned surface with further lines of desired characteristics in contour, spacing and the like, all lines having such relationship that apparent movement and changes in colour and pattern will occur as the observer changes his viewpoint.

Figures 1 and 2 show straight lines 12a crossed at right angles. Figure 5 shows sinuous lines 12b crossed at approximately right angles. From printer's blocks bearing these simple arrangements of lines innumerable different designs or patterns may be obtained which do not resemble the lined appearance of the blocks and which may radically differ from each other in appearance. A surface printed with a lined block may be returned and over-printed by the same block at an angle thereto, that is the printed surface is applied to the block at an angle thereto when the second or over-printing is being made. The patterning and/or colour effects which result are surprising and the new pattern obtained will appear and be repeated over the whole surface corresponding to the number of times the lines cross each other, that is, dependent upon

the angle of the over-print. Over-printing may also be effected at an angle to any of the blocks used when multiple patterns are being formed. A print obtained from a right angular straight 5 lined block, for example, angularly over-printed with a right angular sinuous lined block will result in a wavy round-like pattern repeated on the sheet as often as the lines are crossed or interfere with each other and another different pattern 10 may be obtained simply by varying the angle of the over-print, that is the angle between the line printed surface and the block when the second or over-printing is made. Similarly a straight lined block having simple lines in one 15 direction, when used horizontally to over-print a surface printed from a block having sinuous lines, will with lines of a similar width, produce a pronounced wavy pattern. No angular relationship 20 between the over-printing block and the lined sheet first printed is required in this case but the lines will require to both be arranged horizontally as previously mentioned. Nevertheless a printed surface may be over-printed at an angle to either of the blocks to obtain variation. 25 Sinuous lined blocks, as in Fig. 5, may be used individually or in conjunction to produce lace-like patterns by over-printing and entirely different patterns may be obtained by varying the 30 printing angles as above indicated and by using blocks having sinuous lines the corrugations of which are of different length or pitch. The number of different patterns obtainable from a few blocks bearing simple lines is remarkable and the colour effects obtainable are surprising. Blocks 35 having comparatively complex line patterns thereon and different line contours and complicated line designs may of course be used: simple lines have been used herein for clearness. Figure 4 shows crinkly lines 12d which, whether used as 40 shown or crossed at right angles or otherwise, by over-printing in conjunction with straight lines, such as are shown in Figures 1 and 2, or in conjunction with sinuous lines, such as are shown in Figure 5, of appropriate spacing or pitch, will 45 produce step-like straight or waved patterns resembling or strongly suggesting knitted goods, hosiery and the like and accordingly very useful with appropriate printed matter and in illustrations of such goods. Patterned paper printed by 50 lined blocks in the manner herein-indicated is particularly useful for covering cartons and the like and printed stocks of papers, embossed or unembossed, may always be changed to a different pattern simply by an additional printing with one 55 of the blocks already used in its production, applied at an appropriate angle, or by the use of another appropriate block. Such papers also may possess an appearance of texture and if necessary may be roughened or grained by known 60 apparatus to enhance their appearance, particularly when textile goods are being imitated. The effect of embossing patterned papers such as those above described with parallel or substantially parallel lines, angularly or otherwise applied, is 65 to introduce further patterns and/or effects. In simple explanation of this it may be assumed that a paper printed with the line arrangement shown in Figure 5 has been embossed with appropriate straight lines applied diagonally: when 70 viewed frontally the line arrangement seen in Figure 5 alone will be seen but when angularly viewed a tortuous pattern is clearly seen. Obviously any appropriate embossment may be used on any of the printed papers whether of simple 75 or complex pattern and remarkable results in

5
patterning and/or colour change may be obtained. But change of appearance is not always desirable, in some textile imitations or resemblances for example, and embossing must accordingly be made with due regard to circumstances and results required. It should also be understood that over-printing a line printed surface with an arrangement of lines produces a pattern which if not embossed according to this invention remains unchanged when viewed 10 frontally or angularly. If, however, the surface as first printed is embossed with lines corresponding with the second printing, the embossment being made in lieu of the second printing, the surface will remain unchanged and will appear as 15 when first printed when viewed frontally but when viewed angularly the pattern caused by the embossment will be seen and this pattern will correspond with that which would be produced by the second or overprinting referred to. The 20 embossing block or plate, further may in some circumstances be first inked and thereby function in a dual capacity. A surface printed in one colour from a block having an arrangement of lines such as that shown in Figures 1 and 2 if 25 embossed with an appropriate embossing plate or block which has been inked beforehand will provide a very different result or appearance to that seen in the figures. Pyramidal embossments are hereinafter described and would be 30 suitable to obtain a dapple-like effect in the present instance but if used in the manner above-indicated could be slightly flattened at the apex or ridges to provide an inking surface as will be hereinafter more fully understood. An embossing block so used presses the ink down into the 35 grooves or channels formed. Further, an embossing block according to the invention, if also used as an inking block when embossing, may provide a distinct variation in the pattern or form 40 a different pattern, result and/or colour effects.

45
In some circumstances, such as when a line printed surface forms part of a block bearing solid matter or illustration, it will not be practicable to angularly over-print to obtain line patterns in the manner hereinbefore indicated as exact registration of the solid or illustrative matter will be required in successive impressions. A second or additional block, however, 50 may be used having the lines desired at the required angle so that when the line printed portion of the surface is over-printed by the second block the desired pattern will be formed by the over-printing operation without de-aligning matter which requires exact registration. When 55 printing ordinary illustrations in two or more colours with line patterns in accordance with the invention added as backgrounds, for example, the usual colour blocks used may obviously carry desired lines at varying angles in accordance with this invention so that when successive impressions are made to print the coloured illustration the lined patterns desired will be formed by the crossing of the lines of each block.

60
Figure 3 shows a simple arrangement of lines 65 depicted to explain colour effects obtained under some circumstances. The vertical lines 13a are crossed by sinuous lines 13b of similar spacing. Formed between the crossed lines or at the intersection thereof are open spaces or interstices 70 indicated at 13c. Now if the lines are printed in certain colours the interstices, which are unprinted, will appear to the eye to be coloured. For example if the vertical lines 13a are printed with a violet ink on a white surface and over- 75

printed with black sinuous lines 13b the interstices 13c will appear to be coloured yellow. That portion of the vertical lines 13a which is located between the sinuous lines 13b, indicated at 13d, 5 of course remains violet with the result that the printed illustration appears with vertically zig-zagged lines or bars of violet and black between which are laterally located formations or bars of yellow. In coloured patterns or designs 10 formed in the manner hereinbefore described it is obvious that under some circumstances colour effects will be obtained without actually printing some of the colours which appear to be definitely present. Illusive colours obtained 15 in this manner will appear on an embossed surface when viewed frontally but will not under ordinary circumstances appear when the surface is viewed angularly but nevertheless as tinges of colour, a glow, haze and/or complementary effect 20 may be obtained in some circumstances unprinted colours may appear to be present in an embossed line design or pattern.

To cheaply obtain colour effects suitable to certain conditions or circumstances multi-colour 25 printing at one impression may be practised. By multi-colour printing at one impression is meant the application at one time of a plurality of bands of different colours across a printer's block so that the surface printed is coloured with 30 a plurality of bands of different colours by one impression of the block. A block may be inked with a multiplicity of bands of different colours at one time by providing an inking roller having separate peripheral ducts or channels formed 35 therein for the several colours. The block inking roller thereby receives a series of separate peripheral bands of different coloured inks which it transfers to the block. In Figure 1 three bands, indicated by the letters A, B, C, of different coloured 40 inks are presumed to have been applied laterally across the lined surface. A printer's block having a surface so lined and inked in this way, would produce a right angularly lined printed surface with its lines printed in three different 45 coloured bands at one impression. Now if this lined multi-coloured surface is returned to the block and over-printed at an angle thereto the lines will be caused to cross each other a number 50 of times dependent upon the angle. In the resultant printing the coloured bands will be patterned by the original colour of the surface, white for example, with intensification of the 55 colours of the bands where the lines over-lap or cross. A dappled effect is obtained in the present 60 illustrative instance and because of the crossed lines the surface possesses an overall texture-like appearance. The patterns obtained in this way, of course, depend upon the contours of the lines and the number of times the pattern 65 is repeated depends upon the angle of the over-print. When a square surface is being printed it may, before being angularly overprinted to produce pattern, be returned to the block at right angles thereto and over-printed to produce 70 the coloured bands at right angles. In Figure 2 the three over-printed right angled bands produced are indicated by the letters D, E, F. The surface now obviously possesses a different colour arrangement and may now be returned to the 75 block at an angle thereto to obtain a patterned effect. Obviously a multi-coloured surface may be over-printed by another block having any other desired arrangement of lines. The variations in colour effects and patterns obtained are innumerable from a few different arrangements

of lines. A multi-colour printed and/or patterned surface may be embossed with appropriate lines to introduce further pattern, colour effects and apparent movement or colour change. 5

From the foregoing it will be clear that unlimited novel patterns may be easily and cheaply produced, particularly in printing, by over-printing coloured parallel or sufficiently parallel lines, whether continuous or dotted or interrupted, or lines of devices or shapes, with substantially parallel lines of the same or other contour and/or pitch or distance apart in such relationship that a patterned effect as distinct from a mere lined appearance is obtained and colours may in some circumstances appear to be present 15 which are not in fact printed. Or a lined surface may be embossed with suitable lines in lieu of or in addition to over-printing to obtain a changing effect and pattern when the surface is viewed angularly, and variation in the relationship of the 20 printed and/or between the printed and embossed lines will cause different patterns and colour effects to result. Embossing with parallel lines of the same contour and pitch as one of the series of lines used in producing a printed pattern will affect that series and provide a more pronounced pattern based on those lines. Although, as previously pointed out, the method of producing patterns by over-printing substantially parallel lines with substantially parallel lines 30 enables almost unlimited different patterns to be produced from a few printer's blocks, which is particularly useful in producing cartons and the like at low cost, embossing a line patterned surface with substantially parallel lines possessing 35 desired contour, pitch or other characterization adds remarkably to the patterning effects and imparts apparent movement when angularly viewed by, in effect, separating the colours at the interpositional points of interference of the 40 lines. Embossing in accordance with the invention has the effect of imparting another pattern which becomes apparent when the surface is viewed angularly whereas over-printing with the same arrangement of lines as an embossment 45 produces the pattern at front view only at which viewpoint it is invisible when caused by embossing. Patterning by over-printed lines and/or embossment as hereinbefore described also will harmonize what ordinarily would be discordant 50 colours. But, as hereinbefore mentioned, it should be remembered that this additive effect caused by embossing with such an arrangement of lines as will cause further patterning and colour effects and apparent movement may be undesirable in some circumstances, as in the imitation of some knitted goods and textiles. Generally coloured schemes will be produced by so arranging coloured inclined or equivalent surfaces that illustrations, configurations, patterns 60 and colours alter or apparently alter or vary according to the angle from which they are viewed and/or illuminated. 55

Under some arrangements of colours a haze or glow of complementary colour may be observed 65 and illusive colours appear to be definitely printed as previously explained. When lined patterns are embossed the invention may be widely used or applied. Glass could be corrugated, channelled and coloured, for example with or without silvered or mirrored portions and with or without portions translucent to light and this could be incorporated in flashing light signs. The invention could also be used in conjunction with various 70 electrical or other apparatus as rotating drums, 75

- heat rotated and other lamp shades, coloured or other lighting devices. The invention, therefore, although retaining the specific methods, arrangements and devices hereinbefore described is 6 not to be construed as limited thereto.
- Further, by the methods of embossing according to the invention the shooting of colours may be effected by printing upon paper and the like, and variegated effects analogous to those of shot 10 silk, are easily obtained. The patterns or designs obtained, the intermingling of the colours, the apparent changes in direction, the streaks, patches, groups and lateral or other bands of colour vary in number, appearance and direction 15 with the over-printing and number of colours employed and with the angles at which the lines are crossed and/or the angle at which the embossment is applied and with variation of the lines and embossments whether straight, sinuous 20 circular or other conformation and whether mixed or corresponding in conformation and direction. Simple examples may be given. Presuming a sheet of paper is printed with fine evenly spaced coloured lines of narrow width and 25 the sheet printed in one single colour, red for example, is impressed with a roller, die or embossing block engraved with lines of pyramids or right angled lines of corrugations (see Figure 29) of a pitch corresponding with the printed lines, 30 the embossment being impressed parallel with the printed lines, then the material will more nearly resemble a cloth than paper but there will not be variegation. Assume the same printed sheet, however, is embossed with the 35 die at a slight angle or out of alignment with the printed lines. Frontally it will not show variation but when viewed from either side or end the colouring will appear in red and light bands with a cloth-like texture. Assume a sheet is 40 printed with a second series of lines at a slight angle and is impressed with a pyramidal or corrugated die or roller, lateral bands will appear frontally in colours formed by the intermixing of the colours of the two sets of lines 45 but viewed from either side or end lateral bands of colour will be observed corresponding to the original colours of the lines and whatever colours are formed by their merging. Assume the lines of the last sheet to be printed at an 50 angle approximating a right angle and embossed with a pyramidal die or roller, the increased effects may be observed from any direction. By varying the relationship between the angles of the lines and embossments and 55 the number of colours used beautiful effects may be obtained and the printed embossed paper resembles a shot fabric. The pyramidal embossment or crossed corrugations upon angularly related printed lines obviously provides variation 60 from any angle or viewpoint. Further, by printing volute or concentric lines in various colours, with lines crossed or out of centre and embossing with a pyramidal die, or a circular die, or by printing straight lines embossed with a circular lined die, or vice versa and by analogous 65 combinations of lines and embossments feather-like effects, wood graining appearances and the like may be obtained, and by arranging sectors of angular lines circularly embossed, or vice versa, 70 movement, as a wheel turning, will appear to take place.
- The invention also may be applied to obtain apparent expansion, contraction and movement in predetermined designs as in the flames of a 75 fire illustration for example wherein yellow, red

and suitable coloured lines may be printed into flame like contours at desired angles and embossed so that apparent movement and desired colour changes are obtained. Another popular use would be the application of the invention to 5 illustrations of wood, plumage and other natural subjects where colour changes, shot effects and the like exist.

Advantages in printing on paper and the like are also obtainable in the preparation of the line 10 printing blocks. A master die may be first engraved having the requisite number of lines to the inch. Electro-type printing blocks may be cheaply made from the die. Similarly a master embossing die may be engraved having the requisite number of corrugations or pyramidal forms. Electro-type embossing blocks may be cheaply made from the die. By attaching several electro-type blocks together the area or size may be increased or diminished. Obviously the electros 15 may be cut or shaped to correspond with desired contours and may be curved in any known manner for attachment to rollers if necessary. The lines may then be printed at angles and in colours and the desired embossment applied at a desired angle, and curved, circular or other lines and embossments may be applied, all as pre-determined if necessary by the trial use of transparent 20 sheets or screens.

"Glaswrap" and "cellophane" coverings and 30 wrappers, particularly for cartons, would be printed by the line patterning methods hereinbefore described and usually would not be embossed. Transparent wrappers when printed with arrangements of spaced lines of open patterns may 35 be used to produce an entirely different external effect both in patterning and colouring to that of the carton or covered article, at small expense. More intricate lace and curtainlike effects present no material difficulty. "Cellophane" embossed 40 with fine parallel lines or line patterns may be used in some circumstances and arrangements of lines produced by multi-colour printing in one operation but generally any reduction of transparency would be undesirable. Wrappers of tin 45 foil and other or similar material may, of course, be produced by the methods hereinbefore described, also crepe paper having apparently changing effects.

I claim:

1. In the production of variegated surfaces and 50 the like, applying to a surface an arrangement of lines having desired characteristics in contour, color, spacing and the like and embossing the surface with an arrangement of lines having different geometric characteristics in contour, and in such relationship with the lines of the surface that the said lines of the surface assume a patterned effect when embossed.

2. In the production of variegated surfaces and 60 the like, printing a sheet with an arrangement of substantially parallel lines having desired characteristics in contour, color, spacing and the like, and over-printing the initial lines any desired 65 number of times with arrangements of substantially parallel lines having desired characteristics in contour, color, spacing and the like, the initial and over-printed lines being arranged in such relationship that the surface assumes a patterned as distinct from a lined appearance and embossing the patterned surface with an arrangement of lines having desired characteristics in contour, spacing and the like and in such relationship with the lines of the surface that apparent movement 70 and changes in color and pattern take place as 75

the observer changes his viewpoint or as the embossed surface is moved.

3. In the production of variegated surfaces and the like, printing a sheet with an arrangement of substantially parallel lines, over-printing in desired relationship the initial printing with an arrangement of substantially parallel lines, and embossing the sheet under heat with substantially parallel lines.

10 4. In the production of variegated surfaces and the like, printing a sheet with an arrangement of substantially parallel lines, over-printing in desired relationship the initial printing with an arrangement of substantially parallel lines, dampening the sheet and embossing the damped sheet under heat with substantially parallel lines.

15 5. In the production of variegated surfaces and the like, printing in a plurality of colors at one operation on a sheet an arrangement of substantially parallel lines having desired characteristics in contour, color, spacing and the like and returning the printed sheet at right angles to the printing device and over-printing in a plurality of colors the initial lines with the same printing device.

20 6. In the production of variegated surfaces and the like, printing in a plurality of colors at one operation on a sheet an arrangement of substantially parallel lines having desired characteristics in contour, color, spacing and the like and returning the printed sheet at right angles to the printing device and over-printing in a plurality of colors the initial lines with the same printing device and embossing the printed sheet with an arrangement of lines having desired characteristics in contour, spacing and the like.

25 7. In the production of variegated surfaces and the like, printing a sheet with an arrangement of substantially parallel lines having desired characteristics in contour, color, spacing and the like and over-printing the initial lines with an embossing device bearing an arrangement of lines having desired characteristics in contour, spacing and the like, the over-printing and embossing being performed in one operation.

30 8. In the production of variegated surfaces and the like, printing in a plurality of colors at

one operation on a sheet an arrangement of substantially parallel lines having desired characteristics in contour, color, spacing and the like and over-printing the initial lines with an embossing device bearing an arrangement of lines having desired characteristics in contour, spacing and the like, the over-printing and embossing being performed in one operation.

35 9. In the production of variegated surfaces and the like, preparing from lined flexible sheets which have been distorted to obtain desired effects a printer's block of each distortion, and over-printing upon each other in appropriate relationship the impressions obtainable from the blocks, to obtain patterned effects uncopyable by ordinary photographic methods without detection.

40 10. In the production of variegated surfaces and the like, printing a sheet with an arrangement of substantially parallel lines having desired characteristics in contour, color, spacing and the like, and over-printing the initial lines any desired number of times with arrangements of substantially parallel lines of desired characteristics in contour, color, spacing and the like, the initial and over-printed lines being printed in such colors and in such relationship that unprinted interstices between the lines appear to be colored.

45 11. In the production of variegated surfaces and the like, printing a sheet with an arrangement of substantially parallel lines having desired characteristics in contour, color, spacing and the like, over-printing the initial lines any desired number of times with arrangements of substantially parallel lines of desired characteristics in contour, color, spacing and the like, the initial and over-printed lines being printed in such colors and in such relationship that a patterned effect is obtained which includes illusory colors apparently but not in reality present, and embossing the patterned surface with an arrangement of lines having desired characteristics in contour, spacing and the like and in such relationship with the lines of the surface that the illusory colors appear to be present and/or disappear with changes of the observer's viewpoint or as the embossed surface is moved.

A. E. TAYLOR.
